(57) **CLAIM**

The ornamental design for a display screen or portion thereof with graphical user interface, as shown and described.

DESCRIPTION

The FIGURE is a front view of a display screen or portion thereof with graphical user interface showing our new design.

The other dashed broken lines in the FIGURE show text and portions of the graphical user interface that form no part of the claimed design.

The dot-dash broken lines in the FIGURE show boundaries that form no part of the claimed design.

1 Claim, 1 Drawing Sheet

UNITED STATES PATENT AND TRADEMARK OFFICE
CERTIFICATE OF CORRECTION

PATENT NO. : D774,072 S
APPLICATION NO. : 29/549465
DATED : December 13, 2016
INVENTOR(S) : Haskins et al.

Page 1 of 1

It is certified that error appears in the above-identified patent and that said Letters Patent is hereby corrected as shown below:

On the Title Page

In the "Description" section, add the sentence "The outermost dashed broken lines in the Figure show a display screen or portion thereof, and form no part of the claimed design." before paragraph 2.

Signed and Sealed this
Twenty-first Day of February, 2017
